FREQUENCY MODULATION

Robert V. Langmuir, Schenectady, N. Y., assignor
to General Electric Company, a corporation of
New York

Application May 22, 1946, Serial No. 671,460

4 Claims. (Cl. 332—5)

1

My invention relates to methods and apparatus for controlling the frequency of high frequency oscillators and more particularly to a method and apparatus which is especially useful for effecting frequency modulation and particularly so with oscillators of the magnetron type.

As is well known in the art of electrical communications, the frequency modulated oscillator constitutes a highly useful tool for the transmission of intelligence by frequency modulation methods, i. e., methods in which continuous variations in the oscillation frequency from a standard frequency constitute a decipherable signal corresponding to the intelligence to be transmitted. To be of optimum practical value such an oscillator must be capable of rapid, continuous and simple adjustment of its frequency throughout a desired frequency spectrum and must be free of distorting factors such as undesirable variations in amplitude (amplitude modulation) which in certain types of oscillators frequently accompany variations in frequency. The usefulness of the magnetron, as a source of oscillations for communication and related purposes has heretofore been limited by inherent characteristics which render difficult frequency modulation meeting this standard.

I have discovered a novel method combining two oscillating elements into a single system in such a manner that readily controllable variations in a common frequency of the elements may be effected and used as desired for the purpose of general frequency control including the transmission of intelligence by frequency modulation methods. While the method is applicable to oscillators of any type it is particularly useful in connection with magnetrons in view of the aforementioned difficulties heretofore experienced in modulating magnetrons. Accordingly, it is the general object of my invention to provide a novel method and apparatus capable of generating high frequency oscillations of continuously variable frequency suitable for frequency modulated transmission of intelligence.

The features of the invention desired to be protected herein are pointed out in the appended claims. The invention itself, together with its further objects and advantages, may best be understood by reference to the following description taken in connection with the appended drawing in which Figs. 1 and 3 represent schematically coupled circuits illustrating the general principles of the invention; Figs. 2 and 4 represent graphs of certain characteristics of the circuits of Figs. 1 and 3 useful in explaining the principle of the

2

invention; Fig. 5 represents schematically a circuit embodying the principles of the invention in connection with oscillators of the type employing electron discharge tubes of the non-magnetron type; while Fig. 6 represents schematically an embodiment of the invention employing magnetron type oscillators.

Generally speaking, I accomplish the objects of the invention by mutually coupling together two oscillating elements which would have different natural frequencies if isolated and permitted to oscillate independently without any mutual coupling between each other. The mutual coupling is accomplished in such fashion that the interaction of the electromagnetic fields of the elements forces them to oscillate at a common frequency which may be caused to vary throughout a substantial frequency spectrum by varying the relative amounts of power supplied to the individual elements.

The general principle of the invention will best be understood from a consideration of the behavior of the coupled circuit shown in Fig. 1. In that figure 10 and 11 represent coupled circuits having slightly different natural resonant frequencies corresponding to wave lengths λ_1 and λ_2 , respectively. The circuits may be considered as mutually coupled by a mutual inductance M. It will be understood that if some convenient source of power having negative resistance characteristics be added to the combined circuit free oscillations may be set up therein. Such a source of power is indicated schematically as power source 12. The combination will, however, oscillate at a common wave length λ differing from both λ_1 and λ_2 . A consideration of the theory of coupled circuits (cf. "Theory of Thermionic Vacuum Tubes" by E. L. Chaffee, first edition (1933, page 378) will indicate that the value of λ for a given value of M can be shown to be a function of the ratio λ_2/λ_1 which function is best illustrated by the curve of Fig. 2 showing the ratio λ_2/λ_1 as ordinates and the ratio of λ_2/λ_1 as abscissae. The precise form of the curve will vary greatly with different values of M but that shown in Fig. 2 may be taken as a qualitative representation of a form of curve which may be obtained by appropriate selection of the coupling M. As hereinafter explained in greater detail, the curve will assume undesirable shapes for extreme values of coupling, i. e., for very tight couplings and for very loose couplings. Suffice it to state at this point that intermediate values of M such as will cause the curve to assume

the general shape indicated in Fig. 2 are preferable.

Assume now for purposes of illustration that λ_2 and λ_1 are given fixed values such that $\lambda_2 > \lambda_1$ (λ_2 is greater than λ_1) i. e., $\lambda_2/\lambda_1 > 1$ (λ_2/λ_1 is greater than 1). If then the system is permitted to oscillate freely under the stimulation from the negative resistance power source 12, the resultant wavelength of free oscillation λ_a will be indicated by some point *a* on the curve of Fig. 2 from which it becomes apparent that $\lambda_a < \lambda_1$ (λ_a is less than λ_1).

Consider next the situation which obtains if the negative resistance power source 12, as indicated in Fig. 3, is transposed to the circuit 11 with all the circuit parameters of both circuits remaining unchanged. A curve similar to Fig. 2 may now be drawn showing the relation of the ratio λ/λ_2 to the ratio λ_1/λ_2 and such is indicated by Fig. 4. Since the circuit parameters are the same as those discussed in connection with Fig. 1, i. e., $\lambda_2 > \lambda_1$ it is obvious that λ_b , the wavelength of free oscillation for this case, will be indicated by some point *b* on the curve of Fig. 4 since $\lambda_1/\lambda_2 < 1$. It follows that $\lambda_b > \lambda_2$ and that λ_b is greater than λ_a . Thus by shifting the power from one circuit to the other a shift in the common frequency of the system has been effected.

Now I have found that if the power be simultaneously applied to both circuits in varying proportions between the condition in which the power is proportionately all in the circuit 10 and that in which it is proportionately all in the circuit 11 it is possible to cause the frequency to shift continuously throughout a substantial range of frequencies between values corresponding to λ_a and λ_b . The analysis of the action in this situation is complicated since it involves phenomena of mutual interaction between the oscillators in circuits 10 and 11 causing them to lock in with each other at a common frequency. It should suffice, however, to state that intermediate between the condition of very tight coupling and that of very loose coupling there may be chosen a value of coupling *M* at which continuous variation in λ may be effected as the power input is gradually shifted from the circuit 10 to the circuit 11, or vice versa. If the coupling is very tight the frequency change will be accomplished as a discontinuous jump from the one extreme to another. On the other hand, if it is too loose both circuits will oscillate independently at different wave lengths.

A complete circuit in which the foregoing principles may be embodied for the purposes of frequency modulation is shown in Fig. 5. In that figure two coupled oscillators 13 and 14 are mutually coupled by mutual inductance *M* between tuned tank circuits 15 and 16 having different natural wave lengths when isolated from each other and connected respectively to oscillating triodes 17 and 18. As will be apparent from the drawing, each of the oscillators 13 and 14 is of the type in which a portion of the power from the oscillating plate tank circuit is inductively fed back to the respective grid circuit to sustain oscillations. Specifically in the case of oscillator 13, the oscillations are sustained in a well known manner in the tank circuit 15 comprising inductance 19 and variable capacitance 20 by means of voltage imposed on the grid 21 by the lower portion 22 of the inductance 19 and the grid lead 23. A grid leak comprising the capacitance 24 and the resistance 25 is provided for the purpose of establishing a fixed bias on the grid in the conventional manner. The anode 26 of the triode 17 is

connected to the tank circuit through a capacitance 27. A thermionic cathode 28 energized by any suitable heater (not shown) supplies the necessary electron currents in the known manner. Except for circuit constants determining its natural wavelength of oscillation, the oscillator 14 may be identical with the oscillator 13 although it need not necessarily be identical. For convenience of illustration it is shown as identical and comprised of corresponding elements which will be apparent by comparison with the oscillator 13. Both oscillators 13 and 14 are energized by a source of anode voltage 29 connected to the respective anodes through secondary 30 of transformer 31 and radio frequency chokes 32 and 33, respectively. For the purpose of extracting energy from the system, a suitable output coil 34 inductively coupled to the tank circuits 15 and 16 may be provided. The coil 34 may be connected to an antenna (not shown) or other agency for utilizing the energy developed by the apparatus.

For the purpose of varying the amount of power supplied to the respective oscillators 13 and 14 in accordance with the principles of the invention, there is provided a modulator circuit indicated generally by the numeral 35. The modulator circuit 35 comprises a pair of amplifier triodes 36 and 37 having respectively anodes 38 and 39, grids 40 and 41, and thermionic cathodes 42 and 43 energized by any suitable heater such as an electrical resistive heater (not shown). A suitable source of power 44 supplies energizing voltage to the anodes 38 and 39 through the medium of a center tapped transformer primary 45 of transformer 31. As indicated, the secondary 30 of the transformer 31 is similarly center tapped and connected in the common anode circuits of the oscillators 13 and 14. Grids 40 and 41 are connected to the cathodes 42 and 43 through opposite halves of the center tapped secondary 46 of a transformer 47. The primary 48 of the transformer 47 may be connected to any suitable source of modulating signals indicated schematically as oscillator 49.

In operation of the circuit of Fig. 5 modulator 35 will serve as a push-pull amplifier which imposes an amplified modulating signal originating in the oscillator 49 upon the secondary 30. In the manner of push-pull amplifiers the transformer 31 will on one half cycle impose a maximum positive voltage on the anode 26 of oscillator 13 and a maximum negative voltage on the corresponding anode of the oscillator 14. During the alternate half cycle, the process will be reversed such that the maximum negative voltage is applied to the oscillator 13 while the maximum positive voltage is applied to the oscillator 14. In this manner the oscillators 13 and 14 will be caused to oscillate with alternately varying amounts of power during the full cycle of the modulating voltage. During one half cycle the oscillator 13 will have a minimum amount of power while the oscillator 14 has a maximum, and during the next half cycle the situation will be reversed. In accordance with the principles of the invention heretofore discussed the oscillation frequency of the system will thereby be caused to fluctuate continuously between maximum and minimum values thereby effecting frequency modulation of the generated electromagnetic energy.

In the circuit of Fig. 6 there is shown a further embodiment of the principle of the invention in connection with oscillators of the magnetron type. In that circuit there are provided magnetron oscil-

lators indicated generally as 50 and 51 each comprising, respectively, split anode magnetrons 52 and 53 and resonant anode circuits comprising, respectively, the lecher wire or equivalent circuits 54 and 55 in which resonant standing waves of the well known type may be developed. As is well understood in the art, such waves will be developed by the appropriate imposition of operating voltages on the anodes of magnetrons 52 and 53 through a suitable source of power 56 connected between the respective cathodes 57 and 58 and the split anodes 59 and 60 of the magnetrons 52 and 53, as shown. It will be understood that the magnetrons will each operate in a magnetic field H directed parallel to the axis of the cathodes 57 and 58 in the well known manner. Such fields may be established by any suitable source (not shown) such as a permanent magnet or electromagnetic coil. The cathodes 57 and 58 may be energized by any suitable heating circuit (not shown).

The resonant systems comprising the lecher wire systems 54 and 55 may be magnetically coupled to each other in a manner similar to that of the coils of Fig. 1 by being closely juxtaposed to each other. However, the coupling may also be accomplished by means of a quarter wave interconnecting line 61 which may comprise a similar lecher wire system or the equivalent such as a coaxial cable of quarter wave length for the desired frequency of operation. It will be understood that such an interconnecting line is roughly the equivalent of an actual inductance insofar as the reflection of impedance between the two circuits is concerned.

For the purpose of varying the amount of power supplied to the respective magnetron oscillators 50 and 51 there may be provided a modulator 62 similar to that provided in the case of Fig. 5. The modulator 62 may comprise a pair of amplifier triodes 63 and 64, having respectively, anodes 65 and 66, grids 67 and 68, and thermionic cathodes 69 and 70 which may be energized by any suitable source of heat such as an electrical resistive heater (not shown). A suitable source of power 71 supplies energizing voltage to the anodes 65 and 66 through the medium of a center tapped transformer primary 72. As indicated, the secondary 73 of the transformer is similarly center tapped and respective halves connected in the anode-cathode circuits of the oscillators 50 and 51. Grids 67 and 68 are connected to the cathodes 69 and 70 through opposite halves of the center tapped secondary 74 of the transformer 75. The secondary 76 of the transformer 75 may be connected to any suitable source of modulating signals indicated schematically as oscillator 77.

In operation it will be assumed that the parameters of the tank currents of the oscillators 50 and 51, 52 and 53 are so chosen that the oscillators would tend to oscillate at somewhat different frequencies if isolated from each other with no mutual coupling. As is well known in the art, magnetron oscillators may be varied in frequency by suitable selection of such parameters as the length of the lecher wire systems in the external circuits. Thus one way of effecting such difference in frequency would be to make one of the lecher wire circuits 54 and 55 slightly longer than the other. In a manner similar to that discussed in connection with Fig. 5 the secondary 73 will on one half cycle impose a maximum positive voltage between the cathode and anode of magnetron 52 and a maximum negative voltage between the corresponding cathode and anode

of magnetron 53. During the alternate half cycle the process will be reversed so that the maximum negative voltage is applied between the cathode and anode of magnetron 52 while the maximum positive voltage is applied between the cathode and anode of magnetron 53. In this manner the oscillators 50 and 51 will be caused to oscillate with varying amounts of power during the full cycle of the modulating voltage. During one half cycle the oscillator 50 will have a minimum amount of power while the oscillator 51 will have a maximum and during the next half cycle the situation will be reversed. In accordance with the principles of the invention heretofore discussed, the oscillation frequency of the system will thereby be caused to fluctuate continuously between maximum and minimum values thereby effecting frequency modulation of the generated electromagnetic waves.

It will be obvious that the principles of the invention may be employed not only for the purposes of the transmission of intelligence by frequency modulation methods but also for frequency control purposes in general. For example, it may be used for tuning purposes where it is desired to tune an oscillating system to a fixed frequency selectable at will within a given range of frequencies. In such case, the relative amounts of power in the respective oscillator heretofore described may be fixed by any suitable means at such values as produce the desired fixed frequency.

It will also be understood that the principles of Fig. 6 may be applied to any type magnetron now common in the art such as the cavity resonator type or the vane type in which oscillations are generated in space resonant cavities positioned about the periphery of a rotating electron space charge of the magnetron type. Similarly, the principles of Fig. 5 may be applied to any of the well known types of electron tubes of the non-magnetic type common in the art. Moreover, any of the known types of anode tank circuits may be used in the place of either the lecher wire circuits 54 and 55 or tank circuits 16; for example, coaxial cable sections of appropriate fractional or multiple wave lengths, or the tank circuits shown in Figs. 5 and 6 may be interchanged between those figures to be used with either of the types of tubes there shown. It will be understood as well that, although I have shown specific forms of mutual coupling between the oscillating circuits, the term "mutual coupling" is used in its broadest sense and may include many other forms of coupling such as capacitative, resistive, or directly connected inductive circuits interconnecting the respective oscillating circuits.

While I have shown and described particular embodiments of my invention, it will be obvious to those skilled in the art that various other changes and modifications may be made without departing from my invention in its broader aspects and I, therefore, aim in the appended claims to cover all such changes and modifications as fall within the true spirit and scope of my invention.

What I claim as new and desire to secure by Letters Patent of the United States is:

1. Apparatus for generating an alternating electrical potential of variable frequency comprising a pair of magnetron oscillators each adjusted to oscillate at a different characteristic frequency when isolated from the other, each of said oscillators including a magnetron and a

resonant transmission line, means coupling said transmission lines of said oscillators whereby the mutual interaction of said lines causes said oscillators to oscillate at a common frequency, power means for energizing each of said oscillators, and means for varying the relative amounts of power in each of said oscillators whereby said common frequency may be varied, said means coupling said transmission lines comprising a transmission line interconnected therebetween and having a length substantially one quarter of the average wavelength of oscillation of said circuit.

2. Apparatus for generating an alternating electrical potential of variable frequency comprising a pair of oscillators each adjusted to oscillate at a different characteristic frequency when isolated from the other, mutual coupling means for coupling the electromagnetic fields of said oscillators whereby the mutual interaction of said fields causes said oscillators to oscillate at a common frequency, power means for imposing an energizing voltage on each of said oscillators, and control means for varying the relative amounts of power in each of said oscillators whereby said common frequency may be varied, said mutual coupling means having an intermediate value of mutual coupling such that said common frequency may be caused to vary continuously throughout a substantial range of frequencies, said control means including a source of alternating voltage and a push-pull amplifier for imposing said voltage upon said oscillators in push-pull manner whereby the voltage upon each of said oscillators varies between a maximum and a minimum value during each cycle of said alternating voltage with substantially 180 degree electrical phase displacement between the voltages upon each oscillator.

3. Apparatus for generating an alternating electrical potential of variable frequency comprising a pair of magnetron oscillators each adjusted to oscillate at a different characteristic frequency when isolated from the other, mutual coupling means for coupling the electromagnetic fields of said oscillators whereby the mutual interaction of said fields causes said oscillators to oscillate at a common frequency, power means for imposing an energizing voltage upon each of said oscillators, and control means for varying the relative amounts of power in each of said oscillators whereby said common frequency may be varied, said mutual coupling means having an intermediate value of mutual coupling such that said common frequency may be caused to vary con-

tinuously throughout a substantial range of frequencies, said control means including a source of alternating voltage and a push-pull amplifier for imposing said voltage upon said oscillators in push-pull manner whereby the voltage upon each of said oscillators varies between a maximum and a minimum value during each cycle of said alternating voltage with substantially 180 degree electrical phase displacement between the voltages to each oscillator.

4. Apparatus for generating a frequency modulated electromagnetic wave comprising a pair of magnetron oscillators each having an anode, a cathode and a resonant transmission line operatively connected to said anode, said transmission lines being adjusted to cause said oscillators to oscillate at different characteristic frequencies when isolated from each other, mutual coupling means for coupling said transmission lines whereby the mutual interaction thereof causes said oscillators to oscillate at a common frequency, said means coupling said transmission lines comprising a transmission line interconnected therebetween and having a length substantially one-quarter of the average wave length of oscillation of said circuit, means imposing an energizing voltage between said anode and cathode in each of said oscillators to sustain oscillation at a common frequency, and means for varying the relative amounts of said energizing voltage in each of said oscillators whereby said common frequency may be varied, said last mentioned means comprising a source of alternating modulating voltage, means for imposing said modulating voltage between said anode and cathode in each of said oscillators in push-pull manner whereby said energizing voltage in each of said oscillators varies between a maximum and a minimum value during each cycle of said alternating modulating voltage with substantially 180 degrees of electrical phase displacement between the variations in the said energizing voltages in each said oscillator.
